(74) Attorney, Agent, or Firm — Scully, Scott, Murphy & Presser, P.C.

(57) **CLAIM**

The ornamental design for a measuring instrument as shown and described.

DESCRIPTION

FIG. 1 is a top-side view of a measuring instrument showing my new design;

FIG. 2 is a top-right perspective view thereof;

FIG. 3 is a top-left perspective view thereof;

FIG. 4 is a back-side view thereof;

FIG. 5 is a left-side view thereof;

FIG. 6 is a right-side view thereof; and,

FIG. 7 is a front-side view thereof.

The broken lines represent portions of the article that form no part of the claimed design.

1 Claim, 7 Drawing Sheets(56)
